HUMIDIFIED CABINET

Charles W. Ward, Rochester, N. Y., assignor to
 Yawman & Erbe Mfg. Co., Rochester, N. Y., a
 corporation of New York

Application February 17, 1934, Serial No. 711,740

1 Claim. (Cl. 312—31)

This invention relates to cabinets and more particularly to cabinets arranged to keep the contents thereof under proper conditions of relative humidity.

5 In the storage of various records, notably in the storage of strips of photographic film, it is essential, if the records are to be preserved without deteriorating, that they be kept in an atmosphere considerably moister than that normally prevailing in a heated room. Furthermore, these records, although they are packed together to save storage space, must be intimately exposed to a moist atmosphere. However, these records are preferably stored where it is undesirable to 15 use a moisture circulating fan or any operating mechanism which requires frequent attention on the part of an attendant.

In accordance with the present invention, a cabinet has been provided for the storage of records, which cabinet satisfies these exacting requirements. The main feature of the invention relates to an arrangement for storing a relatively large amount of liquid in a cabinet and for circulating the moisture therefrom into every 25 part of the cabinet.

For a clearer understanding of the invention, reference is made to the drawing in which Fig. 1 is a perspective view of a cabinet constructed according to this invention; Fig. 2 is a vertical 30 sectional view taken on the line 2—2 of Fig. 1 with the drawer guides and drawer suspensions omitted; Fig. 3 is a vertical sectional view taken on the line 3—3 of Fig. 1, also with the drawer guides and drawer suspensions omitted; Fig. 4 is a detailed sectional view at approximately line 35 4—4 of Fig. 1 indicating the manner in which one of the case strips or guides for supporting the drawer suspensions and the drawers, is mounted on the inner wall of the cabinet, and Fig. 5 is a perspective view of a splashproof container or tray suitable for mounting in the 40 lowest drawer of the cabinet.

In the drawing, 10 designates a cabinet preferably of sheet metal construction closed at its 45 top, bottom and sides, but open at its front. This cabinet has a series of superimposed drawers 11 to 19 inclusive which are mounted on suitable suspension slides 20 and guides or case strips 21, whereby they can be easily inserted and withdrawn from the cabinet. The guides 21 for the 50 drawers are mounted on the respective side walls of the cabinet as indicated in Fig. 4 with their intermediate portions separated therefrom so 55 that the drawers are spaced from one another

and from the inner walls of the cabinet to permit circulation of moisture as indicated by the arrows in Figs. 2 and 3. However, the drawer fronts serve normally to close the open front of the cabinet. 5

In the lowermost part of the cabinet, preferably in the drawer 19, there is provided a receptacle 23 for holding a source of moisture. This source of moisture is preferably a solution of a deliquescent material such as potassium 10 carbonate, presenting a relatively large evaporating surface so that the entire atmosphere within the cabinet is charged with moisture. The receptacle 23, which is preferably removable from the drawer 19, fills substantially the entire space 15 within the drawer. This receptacle is provided with a longitudinal partition 24 and a series of transverse partitions 25 having their lower edges spaced from the receptacle bottom as indicated in Fig. 3. It will be noted that the transverse 20 partitions, which extend at right angles to the direction of movement of the drawer 19 when it is inserted or removed from the cabinet, are spaced relatively close together to prevent the 25 splashing of the liquid when the drawer is being opened or closed. In addition, the upper edges of the receptacle 23 have integrally connected therewith, an enclosing rim 26, the free edges of which are inclined toward the bottom of the receptacle. By this arrangement any 30 of the liquid which splashes over the partitions is accumulated on the rim and then flows back into the receptacle. It will be understood that instead of employing a separate receptacle 23, 35 the drawer 19 itself may be provided with the mentioned partitions and the enclosing rim, but such a construction is less desirable because of the difficulty of keeping it clean.

An instrument 27 for indicating the relative 40 humidity, is mounted in the front face 28 of the cabinet so that its moisture sensitive element is exposed to the atmosphere within the cabinet.

It will be understood that instead of having 45 the drawer fronts close the front of the cabinet, the drawers may be loosely mounted on slides or shelves, and the front of the cabinet can be closed by a suitable door. However, the arrangement herein shown is the preferred arrangement. It will be further understood that 50 instead of providing a liquid in the lower drawer as a source of moisture, this drawer may contain porous material in which the moisture is stored. 55

From the foregoing description, it will be appreciated that a cabinet has been provided having a source of moisture at its lower part and having its drawers so arranged and so mounted within the cabinet, that space either at one or both sides of the drawers or at the rear end of the drawers serves as a vertical flue or flues through which the moisture may rise. It will further be noted that the drawers are spaced from one another so that the moisture rising through the vertical flue or flues, may spread horizontally over the contents of the drawers.

What I claim is:

A cabinet having openings in its front, a series of drawers normally closing said openings, said drawers being supported in spaced relation, one above another on the side walls of the cabinet and in spaced relation to the inner surfaces of said walls, and a tray in the lowermost drawer of the series, said tray having a series of partitions at right angles to the line of movement of said tray when it is withdrawn, said tray also having a rim connected to the upper part of its sides and inclined towards the tray bottom. 5

CHARLES W. WARD. 10
